LUGGAGE CASE

Raymond P. Stoy, White Plains, N.Y., assignor to The Leather Specialty Company, Cincinnati, Ohio, a corporation of Ohio

Filed Oct. 21, 1965, Ser. No. 87,716

Term of patent 14 years

(Cl. D87—5)

FIGURE 1 is a side elevational view of a luggage case showing my new design, both sides being alike;

The essential features of my design are shown in full lines.

I claim:

The ornamental design for a luggage case, as shown and described.
